Letters Patents July 8. 1824.

8291 X

The Schedule referred to in these Letters Patent and, making part of the same, containing a description in the words of the said Seal, how it is
made of his Improvement in a Hatchet which he calls a Hannum
Hatchet.

To all to whom these presents shall come. Be it known that
We the three of the inventors in the County of Worcester and Common-
wealth of Massachusetts have invented a new and useful Improve-
ment in a Harmonia, Watch and that the following is a full and
exact description of the construction and operation of the machine as in-
vented or improved by us.

The Saide Machine consists of a common Hatchet of any convenient size with a head and face like the head and face of a common nail hammer. To this is added the claw of a common nail hammer, placed upon the inner side of the head, and seen with the face of the hammer and standing up towards the handle, and the tang upwards towards the eye. The operation of drawing hawks is performed by lifting the handle. The hatchet is used as the handle, also for breaking, since the hammer drives like other nail hammers. The dimension of said machine consists in the combination of the hammer claw with the hatchet and hammer, head and face.
